UNITED STATES PATENT OFFICE.

CHARLES G. SKILLIN, OF POCOHONTAS, IOWA.

FILM-REWINDER.

1,318,020.

Specification of Letters Patent.

Patented Oct. 7, 1919.

Application filed November 15, 1917. Serial No. 202,210.

To all whom it may concern:

Be it known that I, CHARLES G. SKILLIN, a citizen of the United States, residing at Pocahontas, in the county of Pocahontas and

5 State of Iowa, have invented certain new and useful Improvements in Film-Rewinders, of which the following is a specification.

This invention has relation to moving picture projecting machines, and has for an object to provide means for winding up the film as it is passed through the projecting machine in a manner to permit the reel, when wound, to be transferred to the unwinding support for immediate use without the 15 necessity of rewinding the film.

Another object of the invention is to provide an improved moving picture projecting machine having means for winding up the film as it is fed through the machine 20 from the periphery toward the center of the spiral instead of from the center outward whereby the film may be removed when wound and transferred to the unwinding shaft for immediate use without the 25 necessity of rewinding the film.

Another object of the invention is to provide an improved moving picture projecting machine having the above named characteristics and including a drum upon the 30 winding shaft of the machine wherein to receive the film as it is passed through the projecting machine, winding the film in a spiral from the periphery toward the center, and rollers for supporting the inner convolutions of the film during winding thereof, said rollers being automatically displaced when the film has been formed into a sufficient number of convolutions to be self-sustaining.

40 Another object of the invention is to provide an improved moving picture projecting machine having the above named characteristics, embodying means for directing the film as it is passed through the projecting machine to the drum to wind the film in the manner described above, and a friction type gearing for actuating said film directing means, adapted to permit variation of the film directing means as the convolutions of 45 the winding film decrease in diameter.

In addition to the foregoing my invention comprehends improvements in the details of construction and arrangement of the parts, hereinafter more fully described and particularly set forth in the appended claims.

In the accompanying drawings in which

similar and corresponding parts are designated by the same characters of reference throughout the several views in which they appear:

60 Figure 1, is a view in side elevation of my improvement in projecting machines.

Fig. 2, is a fragmentary view thereof in rear elevation.

Fig. 3, is a view in front elevation of the 65 reel containing box with the door in open position.

Fig. 4, is a detail view on an enlarged 70 scale in section taken on the line 4—4 of Fig. 1.

Fig. 5, is a fragmentary view in plan of the film directing mechanism and

Fig. 6, is a detail section taken on the line 6—6 of Fig. 5.

75 With reference to the drawings, 10 indicates the platform of a moving picture projecting apparatus supporting the projecting mechanism proper indicated at 11, and including a crank shaft 12 for actuating the intermittently operating film shifting mechanism, and a shaft 13 driven by said crank shaft in the usual manner. The reel containing box for containing the unwinding reel is indicated at 14 and is located above the projecting apparatus, while the reel containing box 15 for receiving the projected film is mounted in the usual manner beneath the platform.

85 The lower reel containing box 15 forms a journal for a shaft 16 which supports a 90 winding drum 17 within the box. The drum 17 is open at one end, said open end being directed toward the door of the box, as shown in Fig. 4. Mounted on the floor of the box adjacent the lowest point of the 95 drum 17 is a U-shaped bracket 18 forming a support for a transversely extending shaft 19 which supports a roller 20 of the film directing mechanism, shown in detail in Fig. 6. The roller provided with peripheral projections 21 to enter the marginal perforations of the film, and three small rollers 22 are journaled in the bracket above the roller 20 in arcuate relation, the film indicated at 23 passing from the projecting mechanism 100 11 through an opening in the box 15, and between the roller 20 and said rollers 22.

105 The drum 17 is provided with a small hook 24 upon its inner periphery whereby the unwinding end of the film may, after 110 passing between the rollers 20 and 22 be formed into a plurality of convolutions with

the end of the film on the periphery forming the outermost convolution so that the film may wind from outward to the center of the spiral instead of from the center outward, and the end of the film engaged upon said hook 24.

To support the first formed convolutions of the film against collapse, a plurality of rollers 25 are provided within the upper 10 portion of the drum as shown in Figs. 3 and 4. Each roller is mounted upon a support 26 which is formed with arms 27 and 28 at right angles, the arms 28 extending transversely and horizontally to support the rollers 25, while the arms 27 are directed radially toward the center of the drum 17. The arms 28 extend through radial slots 29 in the cover 30 of the film box 15, while the arms 27 are guided for radial movement in radial housings 31 secured to the outer face of the door or cover 30, the inner end of said housing being open. Coil springs 33 are provided, one for each supporting member 26, said springs having one of their ends connected 25 to the extremities of the arms 27 and the other ends connected to fastenings secured to the housings whereby to normally urge said supports radially outward. As the convolutions increase, each roller 25 and its arm 30 28 move radially inward, while its arm 27 slides radially inward within the housing 31, the spring 33 stretching to permit this movement. Eventually the arm 27 will move so far inward that it passes out of the housing 35 31, and then the contractile action of the spring 33 will result in swinging this arm outward and the other arm 28 inward so that the support pivots around its angle, and the roller 25 will then occupy a position radially 40 within the box 15 instead of parallel with its axis, as shown. This action takes place automatically when the convolutions have increased in number to such a point that the angle of the support passes the inner end of 45 the housing.

The shaft 19 of the film directing mechanism mentioned above projects through an opening in the cover of the reel box, and an arm 34 is provided having an opening in 50 one end to receive said shaft. A bevel gear 35 is then fixedly mounted on the shaft 19 beyond the point of connection of the arm 34 thereto for meshing engagement with a bevel gear 36 which is mounted on the lower 55 end of a shaft 37 disposed in contiguous relation to the arm 34 and mounted in bearings 38 thereon. The opposite end of the shaft 37 is provided with a bevel gear 39 for meshing engagement with a bevel gear 40 60 mounted on a shaft 41 which extends at right angles to the shaft 37 and is mounted in a bearing 42 formed on an enlargement of said arm 34, the opposite end of said shaft being provided with a relatively small friction wheel 43. The friction wheel 43 is

adapted to bear against the face of a friction disk 44 which is mounted upon a horizontal transversely extending shaft 45 in turn journaled in a bearing bracket 46 secured to the rear wall of the lower reel box 70 15 and extending rearwardly thereof. The end of the shaft 45 opposite that end supporting the disk 44 is provided with a belt pulley 47, an endless belt 48 being provided to connect said pulley 47 with a pulley 49 75 mounted on the above mentioned shaft 13 of the film projecting apparatus proper. It will be apparent that by grasping the outer end of the arm 34, the arm may be moved so as to cause the relatively small disk 43 to engage any point on the face of the relatively large disk 44 to vary the speed of transmission of motion from one disk to the other. A second belt pulley 50 is mounted on said shaft 45, and a belt 51 is passed around said 80 pulley 50 and around a pulley 52 mounted on the shaft 16 which is journaled in the lower film box 15.

In operation, the film 23 after passing through the projecting mechanism 11 is convoluted within the drum 17 in the manner mentioned above, and during rotation of the crank shaft 12 as the film is projected, the drum 17 is rotated, power being transmitted thereto through the pulley 49 and belt 48 to 90 the pulley 47, and through the shaft 45 to the shaft 16 through the medium of the pulleys 50 and 52, and the belt 51. The film as fast as it is shifted through the projecting mechanism is taken up by the roller 20 of the 95 film directing mechanism, the roller 20 being actuated through the medium of the disk 44 which transmits power to the disk 43, and through the shaft 41 and bevel gears 40 and 39 to the shaft 37. The power is transmitted 100 from said shaft 37 through the gears 35 and 36 to the shaft 19 of said roller 20. It will be obvious that the speed of rotation of the roller 20 may be varied by moving the arm 34, and contacting the disk 43 with the disk 105 44 at the proper point on said disk 44 to give the requisite speed. As the film is wound within the drum 17 the convolutions become smaller and hence the speed of movement of the roller 20 must be decreased so as 110 to properly direct the film into the drum 17 without entangling the same.

Thus it will be seen that with my improvements in a moving picture projecting machine, the necessity for a film rewinding mechanism is obviated and the time consumed in the use of such mechanism entirely saved. The wear and tear on the film is also saved in view of the fact that the handling necessitated by the use of a rewinding 115 machine is rendered unnecessary.

While I have illustrated and described my invention with some degree of particularity, I realize that in practice various alterations thereover may be made, and I therefore de- 120 125 130

sire to reserve the right and privilege of changing the form of the details of construction, or otherwise altering the arrangement of the correlative parts without departing 5 from the spirit of the invention or the scope of the appended claims.

Having thus described my invention what I claim as new and desire to secure by Letters Patent is:

- 10 1. In combination with a moving picture projection apparatus, a drum to receive the unwinding end of the film therein whereby the film may be wound spirally with the outer convolution formed first, and means 15 for supporting the convolutions during winding of the film, said means being automatically displaceable from engagement with the film when a sufficient number of convolutions have been wound to permit the 20 spiral to be self-sustaining.
2. In combination with a moving picture projection apparatus, a drum mounted for rotation wherein to wind the unwinding end of the film in spiral formation, forming the 25 outer convolutions first, a plurality of rollers projecting into the drum to support the convolutions, means for supporting said rollers movable radially relative to the center of the drum, resilient means urging said roller 30 supporting means outward, and guiding means for said roller supporting means, adapted, when the convolutions have increased to a predetermined number, to permit movement of the rollers out of the drum.
- 35 3. In combination with a moving picture projection apparatus, a reel box, a drum mounted therein to receive the unwinding end of the film whereby the film may be wound spirally therein forming the outer 40 convolutions first, a plurality of radial housings on said reel box, a plurality of roller supports in the form of right angular members having one of their arms within the housing, rollers supported upon their other 45 arms to support the convolutions of the film, and springs urging said roller supports outward, said housings having their inner ends open whereby when the convolutions increase to a predetermined number, the arms 50 within the housings will be moved entirely therefrom to permit the roller supports to move the rollers from the drum.
4. In combination with a moving picture projection apparatus, a reel box having a plu-

rality of radial slots in one wall, a housing 55 over each slot open at its inner end at a point radially beyond the inner end of the slot, a drum rotatably mounted within said box, means within the drum for attaching the unwinding end of the film thereto, a 60 plurality of right-angular supports whereof each has one arm mounted in a housing and its other end projecting through a slot in said reel house and carrying a roller adapted to contact with the film within said drum, and yielding means bearing each support radially outward but permitting its movement inward as the convolutions of the film increase within the drum.

5. In combination with a moving picture 70 projection apparatus, a drum mounted for rotation to receive the unwinding end of the film whereby the film may be formed spirally therein, forming the outer convolution first, a roller over which the film is passed 75 to direct the film into the drum, a plurality of rollers in contiguous relation to the first mentioned rollers to retain the film in engagement with the first mentioned roller, and a variable speed mechanism operable by 80 the projection mechanism for rotating said first mentioned roller.

6. In combination with a moving picture projection apparatus, a drum mounted for rotation to receive the unwinding end of the 85 film whereby the film may be wound spirally therein, and the outer convolutions formed first, a roller over which the film is passed to direct the film into the drum, an arm movable about an axis coincident with the axis 90 of rotation of the roller, a shaft mounted on said arm, means for transmitting motion from the shaft to the roller, a friction disk operatively connected to the upper end of the shaft, a second disk for engagement with 95 the first, and means operable by the projection apparatus for rotating the second mentioned disk, said arm being movable to vary the speed of transmission of motion from one disk to the other whereby the roller may 100 be rotated at various speeds relative to the rate of rotation of the drum.

In testimony whereof I affix my signature in presence of two witnesses.

CHARLES G. SKILLIN.
